UNITED STATES PATENT OFFICE.

JOHN SAGE, OF LOCKPORT, NEW YORK.

CARRIAGE-CURTAIN FASTENING.

SPECIFICATION forming part of Letters Patent No. 293,522, dated February 12, 1884.

Application filed November 1, 1883. (No model.)

To all whom it may concern:

Be it known that I, JOHN SAGE, a citizen of the United States of America, residing at Lockport, in the county of Niagara and State 5 of New York, have invented certain new and useful Improvements in Carriage-Curtain Fasteners; and I do hereby declare the following to be a full, clear, and exact description of the invention, such as will enable others skilled in 10 the art to which it appertains to make and use the same, reference being had to the accompanying drawings, and to letters or figures of reference marked thereon, which form a part of this specification.

15 My invention relates to fastening devices for carriage-curtains; and it consists in the improvements hereinafter described, whereby a substitute for the ordinary knob is secured that is more effective and simple in operation, 20 and can be applied to be retained rigidly in position.

In the accompanying drawings, forming a part of this specification, Figure 1 is a perspective view of one of my improved fastening devices. Fig. 2 is a front elevation of sufficient of a carriage-frame to illustrate the application of my improvements. Fig. 3 is a 25 longitudinal section through one of the curtain-eyes and fastening devices. Fig. 4 is a 30 detail section, illustrating a modification; and Fig. 5 is a perspective view, illustrating another modification.

Curtain-fastening devices as heretofore employed consist, essentially, of a headed knob 35 having a base portion to bear against the face to which they were attached, and a cylindrical spindle designed to enter a perforation and retain the knob in position. This device is objectionable, in that it is difficult to pass the 40 head through the openings of the curtain to secure the same.

By my improvements I obviate the above defects and objections.

The fastening device A consists of an angular base, *a*, a central cylindrical portion, *b*, and a neck, *c*, which, being of smaller diameter than the body portion *b*, forms an annular shoulder, *d*. Upon the neck *c* rests a cap, *e*, having the fin-extension *f*.

50 The parts above described may be readily cast of any soft metal, brass being preferable, a pin-extension, *g*, of hard metal, being em-

bedded centrally in the under side of the base. The upper extremity of the neck *c* is riveted to retain the cap in position, but permits the 55 free turning of the same upon said neck.

From the foregoing it will be apparent that the device can be readily and cheaply produced, and that the cap *e* with its fin-extension *f* can be readily passed through a comparatively 60 small and narrow opening therefor in the curtain, and then be turned transversely across said opening to securely retain the curtain.

By constructing the pin-extension *g* of a harder metal and pointed at its end, the device can be readily driven into the carriage-frame. In most cases it is desirable to interpose a washer, *h*, of leather or other suitable material, between the bottom of the cap and the upper face of the shoulder *d*, to prevent the 65 frictional wear of the parts.

As seen in Fig. 1, the fin-extension *f* is much higher than the body of the cap *e*, to facilitate its manipulation in the fastening operations.

As seen in Fig. 2, the openings in the curtain conform to the outline of the cap *e* and fin *f*, the said openings terminating in an angle, *B*, at one portion.

To prevent the curtain from becoming split at the points where said angles *B* occur, and also to properly bind said openings, a plate, *C*, rests upon the outer face of the curtain around the opening, and is provided with a series of teeth, *i*, which pass through the curtain and rigidly clasp a second binding-plate, *D*, notches in the same preventing the displacement of said teeth *i*.

In Fig. 4 the base or bearing plate *a* of the fastening device is elongated, and carries on its under side, near each end, a rivet, *k*, which 80 passes through the curtain and through a plate, *E*, on the inner side of the same, upon which plate the projecting heads of the rivets *k* are upset, to firmly hold the fastening device in position, the plate *E* preventing the rivets from 85 tearing through the cloth.

In Fig. 5 the neck *c* is omitted, the pin-extension *g* extending through the body portion *b* of the fastening, and being threaded at its upper end, to engage a nut, *l*, which prevents 90 the vertical removal of the cap.

It is obvious that the improved fastening is of cheap and ready production, simple and effective in operation, and, in connection with

the other features specified, forms a very secure and desirable fastening.

I claim—

As a new article of manufacture, a fastening device for carriage-curtains, consisting of a body portion, a cap revolving thereon, and a pin-extension or rivet, substantially as set forth.

In testimony whereof I affix my signature in presence of two witnesses.

JOHN SAGE.
